UNITED STATES PATENT OFFICE.

HENRY L. HASKELL, OF LUDINGTON, MICHIGAN.

POOL-TABLE.

No. 857,057.

Specification of Letters Patent.

Patented June 18, 1907.

Application filed August 26, 1903. Serial No. 170,832.

To all whom it may concern:

Be it known that I, HENRY L. HASKELL, a citizen of the United States, residing at the city of Ludington, in the county of Mason and State of Michigan, have invented certain new and useful Improvements in Pool-Tables, of which the following is a specification.

This invention relates to improvements in pool tables.

The objects of this invention are—First: To provide an improved pool table by which the balls pocketed by a particular player may be delivered into a receptacle designated for the use of that player. Second: To provide an improved pool table which is simple in structure and operation, and economical to produce, which is adapted to deliver the balls of a particular player into a receptacle designated for the use of that player.

Further objects, and objects relating to structural details, will definitely appear from the detailed description to follow.

I accomplish the objects of my invention by the devices and means described in the following specification.

The invention is clearly defined and pointed out in the claims.

A structure embodying the features of my invention is fully illustrated in the accompanying drawing forming a part of this specification, in which—

Figure 1 is a plan view of my improved pool table, portions being cut away to show the details of construction. Fig. 2 is a detail transverse sectional view taken on line 2—2 of Fig. 1. Fig. 3 is an enlarged detail sectional view taken on line 3—3 of Fig. 1, showing the arrangement of the parts. Fig.

4 is an enlarged detail view taken on line 4—4 of Fig. 1, showing the structure of the general receptacle. Fig. 5 is an enlarged detail cross-sectional view taken on line 5—5

of Fig. 2, through one of the delivery troughs or carriers. Fig. 6 is an enlarged detail view taken on a line corresponding to line 6—6 of Fig. 7, showing the lock for the trip rod *r*. Fig. 7 is an enlarged detail sec-

50 tional view taken on line 7—7 of Fig. 6. Fig. 8 is an enlarged detail sectional view of a modified form of operating connection for the trip rods *r*. Fig. 9 is a front elevation view of the structure appearing in Fig. 8.

55 In the drawing, the sectional views are taken looking in the direction of the little

arrows at the ends of the section lines, and similar letters of reference refer to similar parts throughout the several views.

Referring to the lettered parts of the drawing, *A* represents the frame upon which the bed *A'* of the table is supported, and also the operating parts. The pockets *B* are connected to deliver into troughs or chutes *b*, delivering into the centrally arranged general receptacle *C*. The general receptacle *C* is provided with a valve or false bottom *C'*, which is yieldingly supported on the centrally arranged coiled spring *c*. Projecting upwardly from the center of the false bottom or valve *C'* is a stem *C''*, to the upper end of which the trip rods *r* are secured. The trip rods *r* are arranged through key-hole slots *s'* in the guides *s* on the frame *A*. The key-hole slots *s'* are adapted to engage the adjustable stops *r'* on the ends of the trip rods *r* which are threaded to receive the same. A suitable knurled hand-piece *r''* is provided for the end of the rod. These trip rods are provided one for each side of the table, or one for each player.

The receptacle *C* is supported on a pair of cross-pieces or trusses *E* (see Figs. 1 and 2), through which the bolts *E'* are arranged. The receptacle *C* is provided with a slot *f* in each side through which the balls escape when the valve is properly tilted. When the false bottom *C'* is in its normal position, it is engaged by the downwardly projecting stops *i*. These stops *i* serve as bearings when the valve is operated. These stops *e* are provided to limit the downward movement of the valve or false bottom, the parts clearly appearing in Figs. 1, 2, and 4.

An individual receptacle *D* is provided for each player. Delivery chutes or troughs *d* lead from the delivery openings *f* of the general receptacle *C* to the players' receptacles.

The troughs *b* and *d* are preferably formed of canvas or the like, as this material is economical and readily applied.

In the modified structure shown in Figs. 8 and 9, the ends of the trip rods engage cam-shaped slots in the lever *S'*, which are carried by the bracket *S* on the frame of the table, the operation of the device appearing in Fig. 8.

In operation, the pocketed balls are delivered into the central or general receptacle *C*. When a player's turn is ended, if any of the balls have been pocketed, the player trips the valve by means of the trip rod for

the individual receptacle designated for him, and the balls are delivered into that particular player's receptacle; or, if desired, the valve may be locked open so that the balls 5 pass immediately by way of the general receptacle into the particular player's receptacle as soon as pocketed.

The adjustable stops *r* may be adjusted to 10 properly engage the key-hole slot, and operate the valve properly, and lock the same in its open position.

With the parts thus arranged, accurate fitting is not required. The structure is 15 convenient to operate, economical to use, and durable in use.

Numerous structural variations will readily appear to those skilled in the art to which my invention relates.

Having thus described my invention, what 20 I claim as new and desire to secure by Letters Patent is:—

1. The combination with a pool table of a centrally arranged general receptacle; troughs or chutes from the pockets of said 25 table to said general receptacle; a valve for said general receptacle; a centrally arranged spring support therefor; stops for said valve on each side of said receptacle, adapted to serve as bearings therefor; an upwardly projecting stem on said valve; trip rods connected to said stem; guide plates having key-hole slots therein adapted to receive said trip rods; adjustable stops on said trip rods; delivery openings in the side of said general receptacle; stops on each side of said receptacle for limiting the movement of said valve; individual receptacles; and suitable troughs from said general receptacle to said individual receptacles, for the purpose specified. 35

2. The combination with a pool table of a centrally arranged general receptacle; troughs or chutes from the pockets of said table to said general receptacle; a valve for said general receptacle; a centrally arranged spring support therefor; stops for said valve on each side of said receptacle, adapted to serve as bearings therefor; an upwardly projecting stem on said valve; trip rods connected to said stem; guide plates having key-hole 40 slots therein, adapted to receive said trip rods; adjustable stops on said trip rods; delivery openings in the sides of said general receptacle; and suitable troughs from said general receptacle to said individual receptacles, for the purpose specified. 45

3. The combination with a pool table of a centrally arranged general receptacle; troughs or chutes from the pockets of said table to said general receptacle; a valve for said general receptacle; a centrally arranged spring support therefor; stops for said valve on each side of said receptacle, adapted to serve as bearings therefor; an upwardly projecting stem on said valve; trip rods connected to said stem; guide plates having key-hole 50 slots therein, adapted to receive said trip rods; adjustable stops on said trip rods; delivery openings in the sides of said general receptacle; and suitable troughs from said general receptacle to said individual receptacles, for the purpose specified. 55

60

6. The combination with a pool table of a centrally arranged general receptacle; troughs or chutes from the pockets of said table to said general receptacle; a valve for said general receptacle; a centrally arranged spring support therefor; stops for said valve on each side of said receptacle, adapted to serve as bearings therefor; an upwardly projecting stem on said valve; trip rods connected to said stem; guide plates having key-hole 65

slots therein adapted to receive said trip rods; delivery openings in the sides of said general receptacle; stops on each side of said receptacle for limiting the movement of said valve; individual receptacles; and suitable troughs from said general receptacle to said individual receptacles, for the purpose specified. 70

4. The combination with a pool table of a centrally arranged general receptacle; troughs or chutes from the pockets of said table to said general receptacle; a valve for said general receptacle; a centrally arranged spring support therefor; stops for said valve on each side of said receptacle, adapted to serve as bearings therefor; an upwardly projecting stem on said valve; trip rods connected to said stem; guide plates having key hole slots therein adapted to receive said trip rods; delivery openings in the sides of said general receptacle; and suitable troughs from said general receptacle to said individual receptacles, for the purpose specified. 80

5. The combination with a pool table of a centrally arranged general receptacle; troughs or chutes from the pockets of said table to said general receptacle; a valve for said general receptacle; a centrally arranged spring support therefor; stops for said valve on each side of said receptacle, adapted to serve as bearings therefor; an upwardly projecting stem on said valve; trip rods connected to said stem; delivery openings in the sides of said general receptacle; stops on each side of said receptacle for limiting the movement of said valve; individual receptacles; and suitable troughs from said general receptacle to said individual receptacles, for the purpose specified. 90

6. The combination with a pool table of a centrally arranged general receptacle; troughs or chutes from the pockets of said table to said general receptacle; a valve for said general receptacle; a centrally arranged spring support therefor; stops for said valve on each side of said receptacle, adapted to serve as bearings therefor; an upwardly projecting stem on said valve; trip rods connected to said stem; delivery openings in the sides of said general receptacle; and suitable troughs from said general receptacle to said individual receptacles, for the purpose specified. 100

7. The combination with a pool table of a general receptacle suitably connected to the pockets thereof; a tilting valve for said general receptacle; a spring support therefor; an upwardly projecting stem on said valve; trip rods connected to said stem; means for locking said trip rods; delivery openings in the sides of said general receptacle; and individual receptacles suitably connected to said general receptacle, for the purpose specified. 110

8. The combination with a pool table of a general receptacle suitably connected to the pockets thereof; a tilting valve for said general receptacle; a spring support therefor; an upwardly projecting stem on said valve; trip rods connected to said stem; means for locking said trip rods; delivery openings in the sides of said general receptacle; and individual receptacles suitably connected to said general receptacle, for the purpose specified. 120

- a general receptacle suitably connected to the pockets thereof; a tilting valve for said general receptacle; an upwardly projecting stem on said valve; trip rods connected to 5 said stem; means for locking said trip rods; delivery openings in the sides of said general receptacle; and individual receptacles suitably connected to said general receptacle, for the purpose specified.
10. 9. The combination with a pool table of a general receptacle having a plurality of delivery openings in the sides thereof; troughs or chutes from the pockets of said table to said general receptacle; a tilting valve for 15 said general receptacle adapted to control the delivery of balls through said openings thereof; a spring support for said valve; a stem for said valve; trip rods connected to said stem; and individual receptacles suitably connected to said general receptacle, for the purpose specified.
10. 10. The combination with a pool table of a general receptacle having a plurality of delivery openings in the sides thereof; troughs or chutes from the pockets of said table to 20 said general receptacle; a tilting valve for said general receptacle adapted to control the delivery of balls through the said openings thereof; a return spring for said valve; trip rods for said valve; and individual receptacles suitably connected with said general receptacle, for the purpose specified.
15. 11. The combination with a pool table of a general receptacle having a plurality of delivery openings in the sides thereof; troughs or chutes connecting said general receptacle with the pockets of said table; a valve for said receptacle adapted to control the delivery of balls through the said openings thereof; a return spring for said valve; trip rods for said valve; and individual receptacles 25 suitably connected to said general receptacle, for the purpose specified.

In witness whereof, I have hereunto set my hand and seal in the presence of two witnesses.
